CONVERTIBLE BRIDGE AND POKER TABLE TOPS

William F. McMechen, Yorktown Village, Md., assignor of one-half to Herbert J. Jacobi, Washington, D.C.

Filed Nov. 24, 1958, Ser. No. 775,884

7 Claims. (Cl. 312—285)

This invention relates to furniture and more particularly to a table top which may be conveniently converted for use as a bridge or poker table.

As is well known, a bridge table is commonly rectangular and presents a smooth upper surface for receiving the cards while a poker table may be rectangular or of other shapes and is commonly provided with pockets or shelves around the outside thereof to receive poker chips or other articles. Heretofore, removable shelves have been provided to be secured to the edge of a bridge table for supporting beverage containers or other articles and there have also been proposed shelves or compartments which may be attached to a bridge table for receiving poker chips or other articles. These prior art devices, however, were somewhat inconvenient to store and utilize since the article supporting shelves were separate from the table and must be separately stored and applied when it is desired to utilize the same and consequently considerable effort is required and also there is the ever present danger that these removable shelves will be broken or misplaced.

It is accordingly an object of the invention to provide a convertible bridge and poker table top having shelves providing compartments for receiving poker chips or the like and which shelves may be pivotally moved to an extended position for use as a poker table or may be moved into recesses which completely house the shelves and permit use of the device as a bridge table.

A further object of the invention is the provision of a convertible bridge and poker table top which may be provided with foldable legs or which may be provided merely in the form of a table top which may be supported on a conventional bridge table or other suitable supporting means.

A still further object of the invention is the provision of a convertible bridge and poker table top in which a triangular recess is provided in each side edge of the table top for receiving a shelf which is pivotally mounted on the table top and movable out of the recess to a position in alignment with a side edge of the table and projecting therefrom or movable into the recess for housing the shelf with the outer side wall of each shelf in alignment with the adjacent side edge of the table in order to provide a table top convenient for bridge playing.

Another object of the invention is the provision of a convertible bridge and poker table top having a frame provided by diagonal members and with top and bottom walls on opposite sides of the frame, the space between the top and bottom walls providing triangular recesses for receiving pivotally mounted shelves which may be moved outwardly to provide a poker table top and which may be moved into the recesses and completely housed therein to provide a bridge table top.

A further object of the invention is the provision of a convertible bridge and poker table top having a frame provided by diagonal members and top and bottom walls on opposite sides of the diagonal members with the bot-

tom wall projecting outwardly of the top wall to provide a shelf extending around the top wall on all sides of the table top.

A still further object of the invention is the provision of a convertible bridge and poker table top having a frame provided by diagonal members and top and bottom walls secured to opposite sides of the diagonal members and with a downwardly opening recess provided in the bottom wall for receiving the top of a suitable supporting member.

Further objects and advantages of the invention will be apparent from the following description taken in conjunction with the accompanying drawings wherein:

Fig. 1 is a top plan view of a convertible bridge and poker table top constructed in accordance with this invention;

Fig. 2 a bottom plan view of the table top shown in Fig. 1 and with supporting legs in folded position;

Fig. 3 a top plan view of the table top shown in Fig. 1 but with movable shelves for converting the table top from a bridge table to a poker table shown in the various positions occupied during operation of the same;

Fig. 4 a top plan view of a table top constructed in accordance with this invention and with the shelves in extended position to provide a poker table top;

Fig. 5 a sectional view taken substantially on the line 5—5 of Fig. 3;

Fig. 6 a fragmentary sectional view taken substantially on the line 6—6 of Fig. 3;

Fig. 7 a fragmentary sectional view taken substantially on the line 7—7 of Fig. 3;

Fig. 8 a top plan view of a slightly modified form of the invention and showing a shelf in dotted outline and in various positions occupied during operation thereof;

Fig. 9 a side elevational view of the table top shown in Fig. 8; and

Fig. 10 a sectional view taken substantially on the line 10—10 of Fig. 8.

With continued reference to the drawings and particularly Figs. 1—7, there is shown a convertible bridge and poker table top constructed in accordance with this invention and which may well comprise a frame provided by diagonal members 10 and 11 secured together as shown in dotted lines in Fig. 3 and to one side of which is secured in any suitable manner a bottom wall 12. A rectangular top wall 13 is secured to the opposite side of the diagonal members 10 and 11 and if desired as shown in Fig. 5, the bottom wall 12 may be provided with a downwardly extending peripheral flange 14. If desired, foldable legs 15, 16, 17 and 18 may be mounted on the bottom wall 12 by suitable hinge and locking means 19, 20, 21 and 22 and this leg and mounting structure is similar to the conventional foldable legs utilized on ordinary bridge tables. If desired, the folding legs may be completely omitted and the table top of this invention supported on a conventional bridge table or other suitable support.

The diagonal members 10 and 11 together with the bottom and top walls 12 and 13 provide outwardly opening triangular recesses 23, 24, 25 and 26 in each side edge of the table top and these recesses serve to receive and house triangular shelves 27, 28, 29 and 30, respectively. Each of the triangular shelves are provided with upstanding inner side walls 31 and 32, an outer side wall 33 and a central upstanding partition 34 extending from the apex of the inner side walls 31 and 32 to the outer side wall 33 to divide each shelf into two compartments 35 and 36 having a common bottom wall 37.

Each of the shelves 27, 28, 29 and 30 is hingedly mounted on the diagonal members 10 and 11 adjacent the corners of the table top by means of hinge plates

38 and 39 secured to the outer side wall 33 of each shelf at one end of the side wall 33 and with the outer end of each diagonal member 10 and 11 received between the metallic hinge members 38 and 39 there being a hinge pin 40 extending through the hinge members 38 and 39 and to the diagonal members 10 and 11 to pivotally mount each shelf for swinging movement in a horizontal plane.

As shown in Figs. 1 and 2, the shelves 27, 28, 29 and 30 may be received in the triangular recesses 23, 24, 25 and 26 to completely house the shelves within the confines of the table top and in this condition the table top is suitable for use as a bridge table. When it is desired to convert the same for use as a poker table, the shelves are swung outwardly from the triangular recesses in the direction of the arrows as shown in Fig. 3 it being noted for instance, that the shelf 30 is swung outwardly from the triangular recess 26 to a position as shown in full lines in Fig. 4 and the other shelves are likewise swung outwardly and into position in a similar manner. In this way the table top is provided on all sides with triangular shelves having two compartments for receiving poker chips or the like. When play has been completed or it is desired to convert the table top for use as a bridge table, it is only necessary to swing the shelves 27, 28, 29 and 30 from their extended position as shown in Fig. 4 to their completely housed position in the triangular recesses as shown in Figs. 1 and 2. The shelves may be removably retained in closed or extended position by a suitable detent 41 on the bottom wall 12 which engages in a downwardly opening recess 42 in the under side of the outer side wall 33 of each shelf.

A slightly modified form of the invention is shown in Figs. 8, 9 and 10 and in this form of the invention there may be provided a frame composed of diagonal members 43 and 44 to one side of which is secured a bottom wall 45 and to the upper side of which is secured a top wall 46. As best shown in Fig. 10, the bottom wall 45 extends outwardly of the top wall 46 to provide a marginal shelf 47 extending around the top wall 46 on all sides thereof. Also provided in the bottom wall 45 is a downwardly opening recess 48 of rectangular or other suitable configuration which serves to receive the top 49 of a conventional card table 50 or other suitable means for supporting the table top of this invention.

As in the previous form of the invention described above, the diagonal members 43 and 44 together with the bottom wall 45 and top wall 46 provide outwardly opening triangular recesses on each side of the table top and removably received within these recesses are triangular shelves 51 having upstanding inner side walls 52 and 53 and upstanding outer side wall 54 and a central partition wall 55 extending from the apex of the side walls 52 and 53 to the outer side wall 54 to provide two compartments 56 and 57 having a common bottom wall 58.

The outer end of each diagonal member 43 and 44 is provided with spaced ears 59 and 60 and disposed between these ears is a lug 61 projecting from one end of the outer wall 54 of each shelf 51. A hinge pin 62 extends through the ears 59 and 60 and the lug 61 to pivotally mount each shelf 51 for movement in a horizontal plane into and out of the triangular recesses provided as described above. The triangular shelves 51 are removably held in housed or extended position by means of a spring pressed detent 63 carried by the bottom wall 45, the detent 63 being received in a downwardly opening recess 64 in the lower surface of the outer side wall 54 of each shelf 51.

When it is desired to use the table top shown in Figs. 8-10 as a bridge table the shelves 51 are completely housed within the triangular recesses with the outer side walls 54 in alignment with the side edges of the top wall 46 of the table top and in this condition there is provided the marginal shelf 47 extending around the table top 46 for supporting suitable articles such as beverage con-

tainers or other articles. When it is desired to convert the table top for use as a poker table the shelves 51 are swung outwardly of the triangular recesses to the extended position shown in dotted lines in Fig. 8 at which time there is provided on each side of the table an outwardly extending shelf having the two poker chip or other article receiving compartments 56 and 57 and there is also provided between each shelf at a corner of the table an additional shelf space 65 which may be utilized for any desired purpose.

10 The convertible bridge and poker table top of this invention may be constructed of any desired materials or combination of materials such as wood, plastic, metal or the like and as will be seen from the above, this table top provides an extremely convenient and highly usable article of furniture which may be easily converted for use as a bridge or poker table and also conveniently stored when not in use. The structure is entirely unitary in that no separable parts or elements are utilized and consequently there is no danger of misplacement of parts and little danger of breakage or damage.

15 It will be obvious to those skilled in the art that various changes may be made in the invention without departing from the spirit and scope thereof and therefore the invention is not limited to that which is shown in the drawings and described in the specification, but only as indicated in the appended claims.

20 What is claimed is:

1. A convertible bridge and poker table top comprising 25 a frame provided by diagonal members, a rectangular bottom wall secured to said frame, a rectangular top wall secured to said frame, said diagonal members together with said top and bottom walls providing an outwardly opening triangular recess on each side edge of said table top, a triangular shelf removably received in each recess, each shelf having upstanding side walls and a central upstanding partition dividing each shelf into two compartments, hinge means pivotally mounting each shelf on said frame at one corner of said table top for movement in 30 a horizontal plane, whereby each shelf may be swung out of the recess in one side edge of said table top to a position in alignment with and projecting outwardly of the adjacent side edge of said table top to provide a poker table top and whereby each shelf may be swung into said recesses with the outer wall of each shelf in alignment 35 with the adjacent side edge of said top wall to provide a bridge table top and detent means for releasably holding said shelves in extended or housed position.

40 2. A convertible bridge and poker table top comprising 45 a frame provided by diagonal members, a bottom wall secured to said frame, a top wall secured to said frame, said diagonal members together with said top and bottom walls providing an outwardly opening triangular recess on each side edge of said table top, a triangular shelf removably received in each recess, each shelf having upstanding side walls and hinge means pivotally mounting each shelf on said frame at one corner of said table top for movement in a horizontal plane, whereby each shelf may be swung out of the recess in one side edge of said table top to a position in alignment with 50 and projecting outwardly of the adjacent side edge of said table top to provide a poker table top and whereby each shelf may be swung into said recesses with the outer wall of each shelf in alignment with the adjacent side edge of said top wall to provide a bridge table top.

55 3. A convertible bridge and poker table top as defined 60 in claim 1 in which foldable legs are mounted on said bottom wall.

65 4. A convertible bridge and poker table top as defined 70 in claim 1 in which said hinge means comprises metallic members secured to the outer side wall of each shelf and a hinge pin extending through said members and each diagonal member to pivotally mount each shelf.

75 5. A convertible bridge and poker table top as defined 80 in claim 1 in which said hinge means comprises spaced

ears on the outer end of each diagonal member, a lug projecting from end of the outer side wall of each shelf and disposed between said ears and hinge pins extending through said ears and lugs to pivotally mount each shelf.

6. A convertible bridge and poker table top as defined in claim 1 in which said bottom wall projects outwardly of said top wall to provide additional shelf space at each corner of said table top when said shelves are extended and to provide a shelf on all sides of said table top when said shelves are in housed position.

7. A convertible bridge and poker table top as defined in claim 1 in which said bottom wall is provided with a downwardly opening rectangular recess for receiving the top of a support means.
